(57) **CLAIM**

The ornamental design for a vehicle wheel, as shown and described.

DESCRIPTION

FIG. 1 is a front view of a vehicle wheel, showing my new design;

FIG. 2 is a side elevation view thereof;

FIG. 3 is a rear view thereof; and,

FIG. 4 is a cross sectional view taken along line 4—4 of FIG. 3;

FIG. 5 is a front view of a second embodiment of a vehicle wheel showing my new design;

FIG. 6 is a side elevation view thereof;

FIG. 7 is a rear view thereof; and,

FIG. 8 is a cross sectional view taken along line 8—8 of FIG. 7.
